UNITED STATES PATENT OFFICE.

ANTON J. HAUG, OF NASHUA, NEW HAMPSHIRE.

METHOD OF AND APPARATUS FOR WORKING PAPER STOCK.

Application filed August 18, 1924. Serial No. 732,842.

This invention relates to methods of and apparatus for working paper stock and has for its object the provision of improved methods and appliances which may be employed in preparing crude pulp from raw material, in working the crude pulp into a more refined state, in working over and rendering usable tailings or residue from screened stock, or for other purposes.

For illustrative purposes the invention is herein shown embodied in a machine of the general type illustrated in my former Letters Patent Nos. 1,302,469 dated April 29, 1919, 1,443,410 dated January 30, 1923, and 1,518,922 dated December 9, 1924.

My invention will be best understood by reference to the following description when taken in connection with the accompanying illustration showing one specific embodiment thereof, while its scope will be more particularly pointed out in the appended claims.

In the drawings,—

Fig. 1 is an elevation, principally in longitudinal section, showing a machine embodying one form of the invention;

Fig. 2 is a transverse sectional elevation on the line 2—2 in Fig. 1;

Fig. 3 is a similar section on the line 3—3 in Fig. 1;

Fig. 4 is a detail in plan showing a portion of a scraper blade; and

Fig. 5 is a side elevation showing the variable speed transmission and its relation to the refiner.

Referring to the drawings and to the embodiment of the invention therein illustrated, I have shown the same exemplified in a machine of the type described in my aforesaid patents and application, the same having a body or casing 7 provided with an internal cylindrical shell 9 and carried by suitable supports 11 which rest on the bed plate 13.

The casing is herein fixed, but the same might have a movement of rotation either with or without bodily movement of the rolls hereinafter referred to. A housing 15 secured at one end of the casing contains within it an inlet chamber 17 which is surrounded by a hopper 19 through which stock may be introduced, the latter in its passage to the casing being acted upon by devices hereinafter described.

During the operation of the machine the stock travels from the inlet chamber through the casing to a discharge chamber 21 secured to the opposite ends of the casing 7, there

being provided at the bottom of the discharge chamber an outlet passage 23 through which the worked over stock is discharged.

In its travel through the casing the stock is subjected to a succession of reducing actions by some crushing agency and preferably by means of the heavy rolls 25. Any desired number of rolls may be provided, but herein the machine is equipped with four. The rolls extend lengthwise the cylinder and are adapted to bear against the stock distributed over the inner face thereof, the rolls being carried around the inside of the cylinder by suitable supports outside of the same so that they are caused to move in a closed orbital path while acting to roll over and crush the stock.

To support and drive the rolls the latter have ends of reduced diameter which extend through the opposite end closures of the casing and are supported in journal boxes 27 in which the rolls are journaled preferably through means of roller bearings (not shown). Each journal box 27 is supported at one end of a short roll-carrying arm 29, the opposite end being pivoted on a sleeve or hub 31 fixed on the end of an arm 33 of a four arm spider 35 or roll-carrier which is keyed to the main drive shaft 37. The main drive shaft is supported in bearings 39 and is driven by any suitable source of power (not shown).

The rolls are carried through their orbital path by the rotation of the two supporting spiders 35 at opposite ends of the casing driven by the driving shaft 37. It will be observed, however, that each roll at each end thereof is journaled in the end of the arm 29 which is itself pivoted on the rotary, roll-carrying spider, and in eccentric relation to the shaft, so that the rotation of the shaft and the carrier through centrifugal force acting on the heavy rolls, tends to swing the arm upwardly and move each roll toward the surface of the cylinder so that as the shaft 37 is rotated, it carries with it the spiders 33 and the pivoted arms 29 in which the ends of the rolls are journaled, and the latter are forced centrifugally out against the inner surface of the shell while at the same time they are carried bodily through an orbital path within the shell.

In a machine of this type it has been found desirable to impart by extraneous means a rotary movement to the crushing rolls each about its own axis as well as the

described bodily movement through an orbital path. It is also often desirable to have this rotary movement of the rolls take place at a speed corresponding to a rolling contact of the roll on the surface of the stock. It may, however, be desirable at times to have provision for altering the speed of rotation of the rolls to impart a slight slip thereto either backward or forward with reference to the stock over which the roll is traveling, or to avoid undue friction between the rolls and the shell when the rolls begin to wear.

The described method of supporting the rolls gives opportunity for imparting rotation thereto either at the speed corresponding to true rolling contact with the stock or at any desired rate of speed to get the required backward or forward slip by transmission gearing which is adapted, however, to maintain the same accurate intermeshing relation during any inward or outward movement of the rolls caused by centrifugal action.

For this purpose each roll beyond the outlet end of the machine has secured thereto a driven gear 43 which meshes with a driving pinion 45, the latter fast on a short shaft 46 which is journaled in the roll-carrying arm 29 and hub 31, the gears being represented in Fig. 3 by their pitch lines only to avoid confusion. As the rolls move toward or away from the inner wall of the casing the axis of the gear 43 moves in the arc of a circle about the axis of the gear 45 as a center, so that the distance between centers remains the same and there is no alteration in the intermeshing relation of the two gears. To turn the gear 45 the shaft 46 has secured to the opposite ends thereof a driven gear 47 which meshes with a driving gear 49, the latter fixedly secured to a sleeve 51 mounted on the driving shaft 37 but freely rotatable thereon. The sleeve 51 is rotated in one direction or the other, as the case may be, by any suitable means, as through the pulley 53, thereby imparting the required rotary movement through the described gearing train to the rolls and giving the latter the desired forward or backward slip, or true rolling contact, as the case may be, with reference to the stock being worked on.

To adjustably drive the pulley 53 and the described train of gearing, any suitable speed varying device may be employed, but herein (Fig. 5) I have shown in conventional form a device similar to that disclosed in my application for patent Serial No. 661,418.

This comprises upper and lower reversely arranged cone pulleys 55 and 57 respectively, the lower pulley 57 being driven from the main drive shaft 37 through the pulley 59 and belt 61. The upper pulley 55 is driven from the lower pulley by a belt (not shown),

the position of which lengthwise the axes of the cone pulleys may be shifted by means of a sliding frame (not shown) moved through an adjusting wheel 63. From the upper pulley power is transmitted to the pulley 53 and sleeve 51 by means of a crossed belt 65. By turning the hand wheel 63 the position of the belt with relation to the cones may be adjusted and the sleeve 51 may be rotated in either direction and at varying speeds. While I have herein shown and described for purposes of illustration a conventional form of speed varying mechanism, other devices may be employed for this purpose as well as other forms of transmission gearing for rotating the rolls.

The described form of the invention being designed for continuous operation and for the progressive advance of the stock through the machine while being subjected to successive crushing actions, suitable feeding devices are employed. These herein comprise a series of devices which form in effect a mechanical screw conveyer acting to convey the material from one end of the machine to the other, the material being advanced progressively between each crushing action. In the illustrated example these conveyer devices are in the form of inclined or helical vanes 67 suitably placed to avoid interference with the rolls and herein carried by arms 69 projecting from hubs 71, there being four such vanes and arms for each hub, one between each adjacent pair of rolls. The conveyer as thus constituted extends lengthwise the drum and beyond the effective portions of the rolls so that a number of vanes are located beneath the inlet 17 and the stock, as soon as delivered to the casing, becomes subject to the action of the conveyer.

Preferably the conveyer blades 69 are arranged with a gradually decreasing pitch from the inlet toward the outlet end, as will be clear from Fig. 1, so that the rate of advance of the stock through the machine diminishes toward the outlet. This provides for an increased number of crushings of the stock for a given length of travel as it nears the outlet end and compacts the stock more closely as the crushing operation progresses. This not only secures a better grade of stock and a more efficient operation of the machine, but also prevents an undue wearing of the rolls near the outlet end.

To prevent the stock from building up on the rolls I have provided scraping devices for removing the material therefrom, these being generally similar to those described in my aforesaid pending application. In the present form, however, the scraping devices are in the form of bars 73 (Figs. 1, 2 and 4) having a beveled edge provided at intervals with forked projections 75 forming an open ended slot, the bars being held in slotted lugs

77 formed on the conveyer blade-carrying arms 69 and carrying bolts which pass through the slots in the bars. Each scraping bar is clamped in the lugs 77 so that 5 its edge comes into contact or approximate contact with the surface of the adjoining roll 25.

While the supporting lugs normally hold the scraping bars in fixed relation to the roll 10 the clamping bolts may be loosened at any time and the bar moved toward the roll to compensate for wear in the roll. It will be observed that the supporting lugs are angled so that this adjustment takes place toward 15 the roll and outwardly toward the inner surface of the cylinder, so that, as the roll wears, the adjustment of the bar is outwardly as well as toward the roll and a minimum adjustment of the scraper bar for any given 20 wear in the roll is therefore required.

In order that the apparatus operate continuously and uniformly, it is desirable that there be provided a continuous and uniform feed of the stock. For this purpose there 25 are preferably provided devices adapted to take the stock as fast as it comes to the machine and deliver it evenly and uniformly to the inlet. In the described form of apparatus I have provided for this purpose intermediate 30 the hopper 19 and the inlet 17 rotary devices which are provided with teeth or surface projections, such devices having their axes parallel with the axes of the rolls 25 and being herein provided one on either 35 side of the inlet and preferably driven at different speeds, their action being such as is adapted to break up the masses or bunches of stock and deliver it evenly and uniformly to the machine inlet where it is taken by the 40 conveying devices 67 and delivered to the rolls.

Herein for this purpose I have provided at one side of the hopper 19, immediately below the same, a rotary drum 79 provided 45 with several sets of radial teeth 81, the latter being provided by toothed annular members 83 mounted on the drum 79 with suitable intermediate spacing members to separate the annular members each from the other 50 lengthwise the drum. The drum 79 with its teeth 81 is cooperatively arranged with relation to a similar drum 85 and teeth 87 also arranged below the hopper 19 and on the opposite side of the path which the stock takes 55 in passing from the hopper to the inlet 17. The teeth 87, however, bear a staggered relation to and slightly overlap the opposite teeth 81 so that the material passing to the inlet is subject to the joint action of both 60 sets of teeth.

To render the device more effective for breaking up or shredding the entering stock, the two drums 79 and 85, which are rotated in the direction indicated by the arrows in Fig. 2, are driven at different speeds. For

this purpose the drum 79 is mounted on the shaft 89 having the frame-provided journal 91 and the pulley 93 which latter is driven directly through the belt 95 from the pulley 97 on the main driving shaft 37. Similarly 70 the drum 85 is mounted on the shaft 99 carrying the pulley 101 which is driven by the belt 103 from drive pulley 105. One of the belts, as the belt 103, is crossed so as to cause the toothed shredding wheels to rotate in opposite directions but both downwardly in the direction of the entering stock, and the pulley 101 is of different diameter from that of the pulley 93 to provide for a difference in speed. 80

Preferably there are provided some means for clearing the stock from the shredding wheels, such, for example, as a set of fingers 107, secured to the casing (see Fig. 2) and projecting between the sets of teeth 81 so as to dislodge the stock adhering to the drum between the teeth and prevent it from being carried around with the drum. A similar set of fingers 109 is provided between the teeth 87 on the drum 85. The shredding wheels 90 are capable of being operated at a high rate of speed making it possible to feed stock of high consistency to the machine and providing a steady and uniform feed therefor. The two sets of teeth moving downwardly, 95 one past the other, tend not only to feed the stock uniformly but to separate and break up bunches or masses of the same.

The inlet end of the machine is closed by an end closure plate 111 which is keyed to the shaft 37 and rotates therewith, the same being provided with openings through which the reduced ends of the rolls pass with sufficient clearance to allow the required radial inward or outward movements of the 100 roll. The periphery of the end closure 111 has a grooved joint with a casing 15 to prevent the escape of stock over the edges thereof and is also preferably provided with a series of deflecting blades 113 (only one of 110 which is shown in Fig. 1) which, cooperating with the conveyer vanes 67 working within the inlet end of the casing, tend to force the stock entering the inlet away from the end closure and thereby preventing any 115 substantial leakage of stock through the apertures through which the rolls pass.

At the opposite end of the casing a similar end closure 115 is provided and a similar series of deflecting blades 117 (see Figs. 1 120 and 2) supported by the inside wall of the end closure, the latter serving to force the stock away from the face thereof and cause it to pass through the outlet 23.

While I have herein shown and described 125 for purposes of illustration one specific embodiment of the invention and one particular application thereof, it is to be understood that the same may be applied to various other uses and herein may be embodied in 130

4
various other forms and that the same is not limited to the mechanical details or form or arrangement of parts, but that extensive deviations therefrom may be made without departing from the spirit thereof.

5. Claims:

1. In a machine for working paper stock or the like, the combination with a cylindrical container having a stock inlet and a stock outlet, of means for advancing the stock from the inlet to the outlet, a plurality of rolls extending longitudinally through the cylinder and adapted to engage the material on the inner surface thereof, a main driving shaft extending through the cylinder, roll carrying devices at opposite ends of the cylinder comprising members secured to the shaft and rotatable therewith, roll carrying arms in which said rolls are journaled pivoted on said members in eccentric relation to the shaft whereby rotation thereof tends through swinging movement of the arms to move the rolls automatically toward the inner surface of the cylinder, and means for positively turning the rolls comprising a driven gear in each roll, an intermediate driving gear concentric with the axis of an arm, a sleeve rotatably mounted on the main driving shaft with means for driving the same, a driving gear carried by the sleeve, a driven gear mounted on the arm and meshing with said sleeve-carried driving gear and connected to turn the arm-carried driving gear, and means for varying the rate of rotation of the sleeve.
2. In a machine for working paper stock or the like, the combination with a cylindrical container, of one or more rolls adapted to engage the material on the inner surface thereof, and a rotary roll carrier with means for rotating the same and carry the rolls through an orbital path within the cylinder, said roll being journaled in arms which are pivoted eccentrically with relation to the center of the carrier whereby rotation of the carrier tends to move the rolls outwardly toward the surface of the cylinder.
3. In a machine for working paper stock or the like, the combination with a cylindrical container, of one or more rolls adapted to engage the material on the inner surface thereof, a rotary roll carrier with means for rotating the same and carry the rolls through an orbital path within the cylinder, said roll being journaled in arms which are pivoted eccentrically with relation to the center of the carrier whereby rotation of the carrier tends to move the rolls outwardly toward the surface of the cylinder, and means for driving the roll including a driven gear coaxial with the roll and a driving gear concentric with the axis of said arms.
4. In a machine for working paper stock or the like, a stock container, a cooperating roll adapted to engage material within the

- ittal path, and driving means for positively turning the roll including a gear concentric with the roll and an intermeshing gear co-axial with the pivot.
- 5 11. In a machine for working paper stock or the like, the combination with a stock casing, of a roll, a swinging roll carrying arm the pivot of which is movable through an orbital path, and driving gearing includ- 70 ing a gear co-axial with the roll and an intermeshing gear co-axial with the pivot.
- 10 12. In a machine for working paper stock or the like, the combination with a stock cylinder, of an internal roll, a driving member co-axial with the cylinder, a swinging roll turning member pivotally connected to said driving member at a point which is moved thereby through an orbital path, and means for positively driving the roll includ- 75 ing a gear co-axial with the roll, an intermeshing gear co-axial with the pivot of said swinging carrying member, and a gear co-axial with the driving member.
- 15 13. In a machine for working paper stock or the like, the combination with a stock cylinder, of an internal roll, a driving member co-axial with the cylinder, a swinging roll turning member pivotally connected to said driving member at a point which is moved thereby through an orbital path, and means for positively driving the roll includ- 80 ing a gear co-axial with the roll, an intermeshing gear co-axial with the pivot of said swinging carrying member, a gear co-axial with the driving member but movable independently thereof, and means for turning said last named gear at a variable and controlled rate of speed.
- 20 14. In a machine for working paper stock or other material, the combination with a cylindrical container, of one or more rolls cooperating with the internal surface of said container to subject the material to a crushing action, and obliquely disposed blades for advancing the material lengthwise said rolls and container, the arrangement of said blades being such as to provide for a diminished rate of advance toward the end of the crushing action.
- 25 15. In a machine for working paper stock or other material, the combination with a casing having an outlet and an inlet, of means for subjecting the material to repeated crushings, and mechanical feeding devices to advance the material in the casing in a direction from the inlet toward the outlet during intervals between successive crushings, the rate of advance being diminished toward the outlet.
- 30 16. In a machine for working paper stock or other material, the combination with a casing presenting material receiving surfaces and having an inlet and an outlet, the material being continuously fed to the inlet and withdrawn from the outlet, of rolls op- 85 erating in said casing and adapted to roll the material on said surface, and conveying devices forming in effect a screw container of decreasing pitch toward the outlet, the same acting during the intervals between successive rollings to scrape the rolled material and feed it a predetermined amount and present it at a more advanced point in the subsequent action of the rolls.
- 35 17. A machine for working paper stock or other material, comprising a cylindrical shell having an inlet at one end and an outlet at the opposite end, a rotary shaft carrying inclined blades for advancing the material from the inlet toward the outlet, 90 and rolls movable through an orbital path and arranged in working proximity to the inner surface of said shell and adapted repeatedly to crush the material entering the inlet, the material being advanced by said blades between successive actions to said rolls and the blades being arranged to give a decreased advance of the material near the outlet end of the machine.
- 40 18. The method of working paper stock which consists in moving a rolling agency repeatedly over the stock, advancing the stock between successive rollings, and progressively decreasing the rate of advance.
- 45 19. The method of working paper stock or other material which consists in feeding the stock to a surface, subjecting it thereon to repeated rolling actions between which the stock is advanced, and decreasing the rate of advance toward the end of the roll- 95 ing action.
- 50 20. A machine for working paper stock or other material having a cylindrical container, a driving shaft, rolls carried by the shaft, through an orbital path to crush the material on the inner surface of the container, a closure for the container comprising a head carried by the shaft through which head parts of the rolls project, and devices carried by the head for forcing the 100 stock away from the same.
- 55 21. A machine for working paper stock or other material having a cylindrical container, one or more rolls with means for moving the same through an orbital path 105 to crush the material on the inner surface of the container, a closure for the container through which parts of the rolls project, a stock inlet adjacent the closure, and devices carried by the closure for forcing the 110 stock away from the same.
- 60 22. In a machine for reducing or refining paper stock, the combination with a casing having an inlet and an outlet, of one or more rolls therein, an end closure for the 115 casing through which the rolls pass with a substantial clearance, and devices carried by the end closure for forcing the stock away therefrom.
- 65 23. In a machine for reducing or refining 120

paper stock, the combination with a casing having an inlet and an outlet, of one or more rolls therein adapted to travel through an orbital path through the casing, an end closure for the casing through which the rolls pass with a substantial clearance, said end closure being rotatable with the movement of the rolls, and vanes carried by the end closure for forcing the stock away therefrom.

24. In a machine for working paper stock or other material, the combination with a casing, of a roll adapted to travel in an orbital path to crush material within the casing, a device supported to move cooperatively with the roll to scrape material therefrom, and means for adjusting the device with relation to the roll.

25. In a machine for working paper stock or other material, the combination with a casing, of a roll adapted to travel in an orbital path to crush material within the casing, conveyer blades adapted to convey

material progressively through the casing, a scraper bar supported on the conveyer 25 blades and arranged for removing material from the roll, and means for adjusting the scraper bar.

26. In a machine for working paper stock or other material, the combination with a 30 casing, of a roll adapted to travel through an orbital path within the casing to crush material therein, a scraper bar held with relation to the roll for removing material therefrom, and means for adjusting the bar 35 obliquely toward the roll and the inner surface of the casing.

27. The process of working paper stock or like material which consists in subjecting the material to a succession of crushing 40 actions, subjecting it to a positive mechanical feed between successive actions, and progressively diminishing the rate of feed.

In testimony whereof, I have signed my name to this specification.

ANTON J. HAUG.
